(57) **CLAIM**

The ornamental design for a display screen with animated playlist graphical user interface, as shown and described.

DESCRIPTION

FIG. 1 is a front view of a first image of a display screen with animated playlist graphical user interface with a highlighted section;

FIG. 2 is a second image thereof wherein the graphical user interface has been rotated;

FIG. 3 is a third image thereof wherein the graphical user interface has been further rotated;

FIG. 4 is a fourth image thereof wherein the graphical user interface has been further rotated; and,

FIG. 5 is a fifth image thereof wherein the graphical user interface has been further rotated.

The graphical user interface transitions sequentially in a scrolling manner among the images shown. The process or period in which one image transitions to another otherwise forms no part of the claimed design.

The broken lines showing an electronic device illustrate environmental subject matter, whereas the broken lines showing a display screen and elements of the graphical user interface illustrate portions of the article. No subject matter depicted in broken lines form part of the claimed design. Crosshatching lines illustrate a highlighted section of the display screen.

The legend shown adjacent to FIG. 1 is only provided for understanding the location of the highlighted section of the display screen in each of the figures, and does not form part of the claimed design.
